United States Patent Office.

JOHN U. FIESTER, OF WINCHESTER, OHIO

Letters Patent No. 65,364, dated June 4, 1867.

FIRE-PLACE.

The Schedule referred to in these Letters Patent and making part of the same.

TO ALL WHOM IT MAY CONCERN:

Be it known that I, JOHN U. FIESTER, of Winchester, in the county of Guernsey, and in the State of Ohio, have invented certain new and useful improvements in the construction of "Fire-Places;" and do hereby declare that the following is a full, clear, and exact description thereof, reference being had to the accompanying drawings, and to the letters of reference marked thereon, in which—

Figure 1 is a front view.

Figure 2 is side section through the centre.

Figure 3 is a section through the line *x x* in fig. 2.

The nature of my invention consists in making a convenient cooking department above the ordinary grate fire, and to avoid the smell arising from the articles cooked, and passing into the room, as will be hereinafter more fully described.

To enable others skilled in the art to make and use my invention, I will proceed to describe its construction and operation.

In the construction of my invention, in fig. 1, A A A represent the fire-place, or I may use a fire-place made of cast iron, and adjustable, to be inserted in the ordinary fire-place or chimney-place, with my improvement attached. I can use either in the construction of my improvement. B the flue at the bottom of the grate, and which admits the draught to the chimney in rear of the grate. C the grate and grate-bars. D the plate above the fire, and is for holding on it the articles to be warmed or cooked, and I may find it necessary to have holes in it in which to put pots, kettles, or other culinary articles. I may also find a door necessary to this open oven or cooking-chamber. E the curved back plate, which fits down close on the fire-plate D, leaving room enough behind it for draught to carry off the products of combustion. This plate is curved so as to bring the top edge against the top and front of the fire-place, as seen in fig. 2, or may be depressed by the key *a*, so as to leave an open space between it and the fire-place, as seen in red lines in fig. 2, leaving an open space above it for any steam or odor from cooking to pass off and up the chimney, as the arrows indicate in said figure. *a* the key passing through the edge of the fire-place, with a cam on its rear end, which is to depress the end or front edge of the curved plate E. *b b* are double flues leading from the fire into the chimney for the purpose of spreading the heat over the bottom of the plate D. F the chimney flue. *d* the bottom on which is set the back of the fire-place *c* and grate C. In fig. 2 like parts are designated by like letters as in fig. 1. The arrows indicate the current of air, and heat, and steam, and odor from the cooking-chamber. In fig. 3 like parts are designated by the same letters as in fig. 1.

In the operation of my invention, if I use the fire-place, the grate is set in the usual way, leaving the flue B behind the grate back, and insert the cast-iron plate D in the fire-place in any convenient way, and also insert the plate E fitting down closely on plate D, and resting in front on supports 1 and 2 in fig. 1, the lower end of said plate having a groove as seen at 3 in fig. 2, setting down snugly on a projection in the rear end of plate D. If I construct an adjustable fire-place of cast iron, I make it to the size required, so that it can be fitted into the fire-place. The grate is fitted into the same in any of the known ways. For so doing leaving the flue B in rear of the grate. The plate D is then fitted into the said adjustable fire-place, and also curved plate E, leaving the flues as described in the rear of the said plates, thus forming a convenient heating and cooking stove, having an open grate fire, and avoiding the odor from cooking in the room. The red lines in fig. 2 show a vessel set on the plate, or it may be allowed to project through the plate, as is done in ordinary cooking stoves. The fire being built in the grate C, the air will rush in at the flue B, as seen at the blue arrow in fig. 2, and the products of combustion will pass off at the flues *b b*, and pass off, as seen by the red arrows in fig. 2, into the chimney, while any steam or odor from cooking will pass off as seen in fig. 2, at the red arrow and red line, showing the plate E pressed down by the key *a* to leave an opening for the same to pass off. The heat from the grate heats the plates D and E, so that I can cook, either by boiling or baking, all kinds of food in the chamber above plate D. I may find it convenient to put a door to this chamber and make it a close oven.

Having thus fully described my invention, what I claim as new, and desire to secure by Letters Patent, is—

The combination of the plates D and E and key *a*, when constructed and arranged as described, and placed over an open fire-grate, the parts operating as set forth and for the purposes described.

In testimony that I claim the above-described invention, I have hereunto signed my name this 8th day of February, 1867.

JOHN U. FIESTER.
